UNITED STATES PATENT OFFICE.

FREDERICK W. WIESEBROCK, OF LONG ISLAND CITY, NEW YORK.

SMOKE-CONSUMING FURNACE AND AIR-HEATER.

SPECIFICATION forming part of Letters Patent No. 398,684, dated February 26, 1889.

Application filed July 19, 1887. Serial No. 244,742. (No model.)

To all whom it may concern:

Be it known that I, FREDERICK W. WIESEBROCK, a citizen of the United States, residing at Long Island City, in the county of Queens 5 and State of New York, have invented new and useful Improvements in Smoke-Consuming Furnaces and Air-Heaters, of which the following is a specification.

In heating air for desiccating, metallurgical, 10 and other purposes it has been the general practice to pass the air over hot surfaces of metal or other material, which method is objectionable in that it demands costly apparatus and seldom utilizes fifty per cent. of the 15 heat generated by the fuel consumed, and is only desirable for warming buildings where the air must be in a condition suitable for respiration, or for drying materials which would be injuriously affected by air mixed 20 with the products of imperfect combustion— carbonic acid and hydrogen. It has also been proposed in this art to heat air by blowing or otherwise forcing it directly through the fire; but this method involves a large consumption 25 of fuel, in that an excessive quantity of air is forced through the fire and imperfect combustion is the result. This not only means a waste of fuel, but the air thus heated is impregnated with sulphurous and carbonic oxides to such an extent as to render it unsuitable 30 for contact with articles of food.

The objects of my invention are to avoid the foregoing objections, to provide a novel air-heating furnace wherein more perfect combustion is obtained, and to purify and place 35 large volumes of hot air in suitable condition to act upon articles of food for desiccating the same or for metallurgical and other purposes. These objects I accomplish by the features of 40 construction and combinations of devices hereinafter described and claimed, reference being made to the accompanying drawings, in which—

Figure 1 is a longitudinal vertical section 45 of a furnace and air-heater constructed according to my invention. Fig. 2 is a transverse vertical section taken through the line *x x* of Fig. 1. Fig. 3 is a front elevation of the furnace. Fig. 4 is a longitudinal section 50 of one of the side walls of the furnace. Fig. 5 is a view, partly in section, of the furnace connected with a drying house or compartment.

The reference-numeral 1 designates a structure of masonry, brick, or iron work, comprising 55 side and end walls, a floor, roof, flues, &c. This structure constituting the body of my furnace and air-heater may be of any desired form and size. At the front of the furnace is arranged the fire-box 2, which has a grate, 3, 6c and the usual charging-door, 4. A door, 5, in the front furnace-wall communicates with the ash-pit, and is provided with a register, 6, for regulating the admission of air to the space beneath the grate and fuel-bed. In rear of 65 the fire-box 2 is arranged the reignition-chamber 7, which is separated from the fire-box by the bridge-wall 8. Above the bridge-wall is arranged an arch-wall, 9, which forms the roof of the fire-box and the reignition-chamber. 70 The bridge-wall 8 does not extend quite up to said arch-wall, leaving a passage, 10, for conveying the products of combustion from the fire-box to the reignition-chamber. The rear wall of the latter has a series of descending 75 or diving openings, 11, formed at its bottom, which lead into a vertical flue, 12, communicating at its top with a chimney, 13, beneath said chimney with an upper longitudinal air-flue, 14, and at its bottom with another air-flue, 15.

The air-flues 14 and 15 extend the entire length of the furnace and open out through the front wall thereof, the upper flue terminating at said front wall and the lower one 85 being carried to any desired point—as, for example, that shown at 31 in Fig. 5—where heated air is required in carrying out desiccating, metallurgical, or other operations.

I have in Fig. 1 shown the lower flue broken 90 off at the point where it may connect with a chamber, which, for the sake of distinction, may be termed the "laboratory." At the other side of the laboratory is arranged another flue, which contains an exhaust-fan, 16, 95 or other device for drawing the air from the furnace and air-heater through the laboratory. At the front of the upper flue, 14, is arranged a slotted register, 30, which serves to regulate the volume of atmospheric air to 10 be heated. The side walls of the furnace are provided with air-ducts 18, which follow a zig-zag course and serve to conduct the air heated by the passage through said ducts into a transverse duct or passage, 19, formed in the bridge-wall. A series of slots, 20, are provided at

the top of the passage 19 for discharging the heated air into the reignition-chamber 7. The air-heating ducts in the side walls of the furnace open out through the front wall thereof, 5 and are provided therewith suitable dampers or registers, 21. The chimney is provided with a suitable damper, 22, and another damper, 23, is arranged in the lower hot-air flue, 15.

10 The operation of a furnace or air-heating apparatus constructed in the above-described manner is as follows, viz: In starting the apparatus, the damper 23 in the hot-air flue 15 is closed, and the damper 22 in the chimney 15 is opened and the fire started in the fire-box. When the furnace becomes well heated, which can be ascertained through the peep-hole 28 in the wall, and when, after admitting air through the ducts in the side walls, a body 20 of white flames is visible in the reignition-chamber 7, the damper in the chimney is closed and the damper in the hot-air flue 15 opened. At the same time the cold-air register 30 in the upper flue, 14, is also opened 25 and the exhaust-fan set in motion. By the use of a pyrometer in the flue 15 the temperature of the air can be ascertained, and the desired degree of heat maintained by admitting more or less air through the register 30. 30 What takes place in the heater itself may be described as follows, viz: The fire being started, the chimney is kept open and the lower flue, 15, closed, and air is admitted to the fire direct through the register in the ash-pit door, while air heated by its passage 35 through the zigzag channels in the side walls of the furnace issues through the slots in the bridge-wall and meets the products of combustion passing over said bridge-wall into the reignition-chamber. This air, passing through the channels in the side and bridge walls, becomes heated by taking up the heat from the walls, and the gases passing from the fire over the bridge-wall mingle with said heated air 40 issuing through the slots in the bridge-wall, and when the temperature of the air reaches from 600° to 700° Fahrenheit said gases are ignited again, thereby consuming the carbonic oxide. This will cause an increase of 45 50 temperature and a final passing out through the slots in the rear wall of the reignition-chamber into the descending or diving flue in rear of said chamber of carbonic acid, hydrogen, and whatever oxygen may be left un- 55 consumed, the bulk of the air being at the same time drawn in through the register 30 and passed over the arch-wall 9, thereby absorbing the heat from said wall, which meets at the discharge-slots in the rear wall of the 60 reignition-chamber the hot products of combustion and becomes well mixed with the same, and is then carried off through the flue 15 to the place of destination for drying, boiling, or heating purposes.

65 The temperature to which air may be heated

in the manner proposed by me varies according to the bulk of the air admitted, and temperatures can be maintained above 1,000° Fahrenheit, and for this reason my invention is especially adapted for metallurgical processes or for drying processes where large bodies of heated air are required. 70

Having thus described my invention, what I claim is—

1. An air-heating furnace for desiccating 75 and similar purposes, provided with a chimney, a fire-chamber, a reigniting-chamber having outlets in its rear wall, a bridge-wall located between the fire-chamber and the reigniting-chamber and containing a channel open 80 at its top to the latter, tortuous passages in the side walls open at the front to the external atmosphere and communicating at the rear with the channel in the bridge-wall, a descending or diving flue located in rear of 85 the reigniting-chamber, and communicating with the rear outlet thereof and with the chimney, a horizontal fresh-air flue extending over the reigniting-chamber and communicating at the rear with the upper part of the 90 diving-flue, and a horizontal flue at the base extending under the reigniting-chamber, and communicating at the rear with the lower part of the diving-flue for conveying the purified hot air therefrom, substantially as described. 95

2. An air-heating furnace for desiccating and similar purposes, provided with a chimney containing a damper, a fire-chamber, a reignition-chamber having outlets in its rear 100 wall, a bridge-wall located between the fire-chamber and reigniting-chamber and containing a channel open at its top to the latter, tortuous passages in the side walls open at the front to the external atmosphere, controlled by valves, and communicating at the rear with the channel in the bridge-wall, an arch over the fire and reigniting chambers arranged to provide a passage above the bridge-wall, a descending or diving flue located at the rear of the reigniting-chamber, 105 and communicating with the rear outlets thereof and with the chimney, a horizontal fresh-air flue extending above the arch, controlled at the front by a valve, and communicating at the rear with the upper part of the diving-flue at a point below the damper in the chimney, and a horizontal flue at the base containing a damper extending under the reigniting and fire chambers, and communicating at the rear with the lower part of the diving-flue for conveying the purified hot air therefrom, substantially as described. 110

In testimony whereof I have affixed my signature in presence of two witnesses.

FREDERICK W. WIESEBROCK.
